UNITED STATES PATENT OFFICE.

RAYMOND J. FAHLE, OF CHICAGO, ILLINOIS.

CONVEYER.

1,227,899.

Specification of Letters Patent. Patented May 29, 1917.

Application filed December 8, 1914. Serial No. 876,092.

To all whom it may concern:

Be it known that I, RAYMOND J. FAHLE, a citizen of the United States, and a resident of the city of Chicago, county of Cook, 5 and State of Illinois, have invented certain new and useful Improvements in Conveyers, of which the following is a specification.

My invention relates to improvements in conveyers designed for use in buildings for 10 conveying articles or material from one floor to another and wherein the unloading from the conveyer is automatically effected.

The object of my invention is the production of a conveyer of the character mentioned which will be of improved construction and efficient in operation.

Other objects will appear hereinafter.

The invention consists in the combinations and arrangements of parts hereinafter described and claimed.

The invention will be best understood by reference to the accompanying drawings forming a part of this specification, and in which,

25 Figure 1 is a section through a building in which is installed a conveyer embodying my invention,

Fig. 2 is a sectional view through the building showing the loading and unloading openings of the various floors communicating with the conveyer shaft, in elevation,

30 Fig. 3 is an enlarged view of a fragment of Fig. 1, parts being shown in section and parts being broken away in order to better illustrate the construction,

Fig. 4 is an enlarged detail sectional view of one of the cars of the conveyer,

Fig. 5 is an enlarged section taken on substantially line $w-w$ of Fig. 1,

40 Fig. 6 is an enlarged section taken on substantially line $x-x$ of Fig. 5,

Fig. 7 is an enlarged section taken on substantially line $y-y$ of Fig. 5,

Fig. 8 is an enlarged fragmentary section 45 taken on substantially line $z-z$ of Fig. 5, and

Fig. 9 is a fragmentary perspective view illustrating the construction of the conveyer cars.

50 The preferred form of construction as illustrated in the drawings is arranged in a vertical shaft 1 formed in the building in which the conveyer is installed. Arranged

at the upper and lower ends of shaft 1 in suitable bearings provided therefor, are spindles 2 and 3 upon which are mounted pairs of spaced coplanar sprocket wheels 4 and 5 respectively. Passing around the sprocket wheels 4 and 5 are endless sprocket chains 6, the central portions of which travel in channel guides 7 which are rigidly supported in shaft 1. The spindle 3 of sprocket wheels 5 is connected by means of a chain or other endless connecting element 8 with a motor 9 or other source of power for driving the chain 6.

Spaced along the chains 6 are cars or carriers, each of which, as clearly shown in Figs. 4, 6, 7, 8 and 9, comprises end pieces 10 provided with slots 11 for embracing transversely extending supporting rods 12, the ends of which are fastened to the chains 6. Coöperating bolts and nuts 13 pass through the members 10 to securely clamp the same upon rods 12. Bolted at their respective ends to end pieces 10 are plates 14 and 15 which are spaced apart by spaced blocks 16, as clearly shown in Fig. 6. The members 14, 15 and 16 are rigidly connected together by bolts and coöperating nuts 17.

The respective ends of members 14 and 15 are provided with extensions 14' and 15' and the end spacing blocks 16' are correspondingly extended to serve as supports for side walls 18 of the car, as clearly shown in Figs. 5 and 6. Secured to the outer sides of plates 14 and 15 are oppositely projecting spaced straps or bars 18' which constitute the rear wall of the car.

Having their rearward ends slidably engaging in the rectangular spaces formed between plates 14 and 15 and blocks 16 are elongated fingers 19 which project forwardly, the outer ends of said fingers engaging between bars 20, the rearward ends of which are secured by screws 21 to plates 14 and 15, as clearly shown in Fig. 9. The bars 20, at opposite sides of each of the fingers 19, are rigidly connected by rivets 22, and intermediate said rivets are provided rollers 23 for engagement with the opposite sides of fingers 19 to permit of ready longitudinal sliding of the latter, this construction being clearly shown in Figs. 4, 7 and 9. The bars 20 between adjacent fingers 19 are preferably formed integral

at their rearward ends, as clearly shown in Fig. 9 and said bars are provided with shoulders 24 for engagement with shoulders 25 provided upon the fingers 19 in order 5 to limit forward sliding of the latter.

The car which is thus formed is alike at top and bottom, one side of the car being used when the same is moving downwardly, and the other side being used when the car 10 is moving upwardly.

Coöperating with the rearward end of each finger 19, as clearly shown in Figs. 4, 7 and 8, is a lever 26 fulcrumed intermediate its ends at 27 to a support 28 secured to and 15 projecting from the plate 14. Carried at one end of the lever 26 is a thimble 28 open at its lower end. Provided at the lower end of said thimble is a movable head or detent member 30, the movement of which in one 20 direction is limited by a nut 31 attached to the outer end of an exteriorly projecting stem of said detent. Said detent is normally held at this terminal of movement by means of a helical compression spring 32. 25 The detent 30 is adapted to normally engage in a slot 33 which is formed in the plate 14, the same being also adapted, upon depression thereof, and with the corresponding finger 19 at its forward terminal of movement, to engage in a slot 34 formed in the adjacent side thereof, as clearly shown in Fig. 8. When said detent 30 is in engagement with the slot 34 of the corresponding finger 19 it will of course lock the latter 30 against sliding movement.

Coöperating with each of the levers 26 is a helical tension spring 35 which serves to normally hold the detent 30 at its outer terminal of movement, that is out of engagement with the corresponding slot 34. 40 The rearward end of each lever 26 is formed with a depending arm 36 which normally is positioned in the path of the corresponding end of the finger 19, as clearly shown in Fig. 4. The arrangement is such therefore, that upon movement of the finger 19 toward the arm 36, the latter will be moved upwardly, and cause rocking of the lever 26 to the position shown in Figs. 7 and 8. All 45 of the levers 26 are connected together by a rod 37 so that all will move in unison and also whereby operation or tilting of one of said levers will correspondingly move all of the others. With this arrangement then, it will be seen that, when one of the fingers 50 19 is slid rearwardly to the position shown in Fig. 7, all of the levers 26 will be operated to depress the heads or detents 30 into engagement with the slots 34 of all of the 55 other fingers 19, as shown in Fig. 8, in order to lock said fingers against sliding movement. The member 30, when in elevated position, is spaced slightly from the corresponding finger 19 so that said member 60 30 will not move into engagement with

said finger until the latter has been moved to such an extent as to bring the slot 34 thereof out of registration with said member 30. Such an arrangement is obviously necessary since otherwise the finger 19 which it was desired to move, would be locked by the detent 30 immediately upon movement of said finger. The provision of compression springs 32, which yieldingly hold the detents 30 at their outer terminals of movement, permits of rearward yielding of the detent coöperating with the finger 19 which has been slid rearwardly, as mentioned, carrying the slot 34 thereof out of registration with said detent, and therefore permits of the movement of all of the other detents 30 into engagement with the slots 34 coöperating therewith.

In the operation of the conveyer it is desired to automatically unload the conveyers at the various floors, and for this purpose unloading openings 38 are provided registering with the various floors at the down-going side of the conveyer and openings 39 are provided at the opposite side of the shaft for registration with the up-going side of the conveyer. The top floor at the down-going side of the conveyer will, of course, not be provided with an unloading opening, since there are no floors above from which deliveries may be made. Correspondingly at the up-going side of the conveyer there will be no unloading opening 39 at the lowermost floor, because there are no lower floors from which deliveries can be made. Provided in the shaft 1 at the lower edge of each of the openings 38 is an unloader 40 consisting of a plurality of spaced fingers, the rearward ends of which are secured to an oscillatory shaft 41 which is mounted in suitable bearings provided upon the walls of shaft 1, as clearly shown in Figs. 1, 3 and 5. The fingers of each unloader 40 are so spaced as to register with the openings between the bars 20 of the conveyer cars so as to permit of passage of said unloader fingers between said car openings upon oscillation of the former. Each of the shafts 41 is provided with a sprocket wheel 42, which is connected by an endless sprocket chain 43 with a sprocket wheel 44 fixed to a shaft 45 which is mounted in bearings secured to a channel supporting beam 46 which is arranged substantially centrally in the shaft 1.

Fixed to each of the shafts 45 is a drum 47 to which is secured one end of a flexible element 48 which is connected at its lower end with a roller head 49 slidably mounted in a substantially vertically extending channel member 50 secured to and depending from the corresponding supporting member 46. The head 49 is provided with an outwardly projecting lug 51 which is positioned in the path of one of the fingers 19

of the conveyer cars, when said finger is at its rearward terminal of movement, as clearly shown in Fig. 3. The arrangement is such that, upon engagement of the lug 51 by one of the fingers 19, causing said lug and hence the member 49 to be carried downwardly, the unloader 40, which normally assumes a depending vertical position, as shown at the lowermost floor at the downward side of the conveyer in Fig. 1, will be rocked upwardly in order to remove any article which may be positioned upon the corresponding car and, upon continued upward movement of said unloader, to discharge the article thus removed from the car through the corresponding unloading opening 38. The lower end of the channel member 50 is curved rearwardly as shown, so that as the member 49 approaches the lower terminal of said member 50, the lug 51 thereof will be retracted from the finger 19 engaging therewith and will finally be moved out of engagement with said finger so as to permit of said lug being returned to its normal position at the upper end of said channel member 50. This return to normal position of the lug 51 is effected through downward swinging of the corresponding unloader 40, which is, of course, effected by gravity. At the lower end of each of the members 50 is provided a curved deflector plate 52 adapted for engagement with the rearwardly projecting finger 19 in order to return the same to its initial position after said finger has disengaged the lug 51, or after said finger has completed the performance of its function. It is of course understood, that the lugs 51 at the various floors will be positioned out of vertical alignment or in such a position that each will be adapted for engagement by a different one of the fingers 19.

The unloading mechanism coöperating with the up-going side of the conveyer is substantially the same as that used in connection with the down-going side of the conveyer, just described, comprising an unloader 40', of substantially the same construction as unloader 40, which is secured to an oscillatory shaft 41' arranged at the lower edge of each of the openings 39. Upon each of the shafts 41' is a sprocket wheel 42' which is connected by means of an endless sprocket chain 43' with a sprocket wheel 44' secured to a shaft 45' mounted in bearings depending from the under side of a channel supporting bar 46' secured in the shaft 1. Upon shaft 45' is fixed a drum 47' to which is secured one end of a flexible element 48', said element 48' passing around a guide pulley 53 and having its other end connected with a head 49' which is slidably mounted in a channel guide member 50' secured to and projecting upwardly from the supporting member 46'. Coöper-

ating with each of the members 49' is a counterbalance weight 54 which is slidably mounted upon a guide rod 55, said counterbalance weight being connected by means of a flexible element 56 with the upper end of the member 49', said member 56 in this arrangement passing over a guide pulley 57. The counterbalance weight serves simply as a means of preventing too sudden return movement of the member 49' after the same has been released from the finger 19, as will be readily understood. A curved plate 52' coöperates with the rearward end of finger 19 after the same has released the corresponding lug 51' in order to return the same to its initial position, serving in the same capacity as the plate 52, above described. For the reception of the articles unloaded, baskets or other suitable receptacles 58 are provided at the lower edge of each of the unloading openings 38 and 39, as clearly shown in Figs. 1 and 2.

The arrangement is such therefore, as will be seen, that a car may be unloaded at any floor desired, providing the proper finger 19 is moved rearwardly so as to engage with the lug 51 or 51', as the case may be, of the floor at which it is desired to unload. To effect this rearward adjustment of the fingers 19, setting mechanism is provided at the lower edge of each loading opening 59 registering with the down-going side of the conveyer and at the upper edge of each loading opening 60 coöperating with the up-going side of the conveyer. The bottom floor registering with the down-going side of the conveyer is of course not provided with a loading opening since there are no floors below to which deliveries can be made, and likewise the top floor at the up-going side of the conveyer is not provided with a loading opening, since there are no floors above to which deliveries may be made. Each of the setting mechanisms for coöperation with the fingers 19 comprises a plurality of arms 61 which are loosely pivoted at 61', as clearly shown in Figs. 1 and 4. Coöperating with the free end of each of the arms 61 is a helical tension spring 62 which normally holds the same at its inner terminal of movement. Also coöperating with each of the arms 61 is a lever 64 fulcrumed at 63, the lever 64 being angular in form so that upon downward rocking of the outer end thereof, the inner end of the lever will engage against the corresponding arm 61 and rock the same inwardly to a position corresponding to the dotted line position of lever 61 shown in Fig. 4. The outer ends of the levers 64 pass through elongated slots 65 provided in plates 66 secured to the outer side of the wall of shaft 1. Adjacent the lower extremity of one edge of each of the slots 65 is formed a detent shoulder 67 which is adapted to frictionally

125

130

engage with the corresponding lever 64 in order to yieldingly hold the same at its lower terminal of movement.

The number of arms 61 arranged at any 5 floor at the down-going side of the conveyer will correspond with the number of floors below the floor in question, and so that in the construction shown in the drawings, the second floor is provided with one 10 arm 61, and the third or upper floor with two of said arms. The arms 61 provided at any one floor are also so positioned as to be adapted for engagement with the fingers 19 which are positioned for registration with the lugs 51 of the floors below and so that in order to effect the discharge of a load at any particular floor, it is only necessary to adjust the lever 64 corresponding with that floor. When this is done, 20 the finger 19 corresponding with the lug 51 at the floor at which it is desired to unload, will be automatically moved rearwardly as the car passes the setting mechanism so that as the car reaches the desired 25 floor, the finger which has thus been set, will engage with the lug 51 of the latter floor and thereby effect automatic unloading of the car. The operation and manipulation of the arms 61 which coöperate with 30 the up-going side of the conveyer are similar to the operation and manipulation of the arms 61 coöperating with the down-going side of the conveyer, just described, and it is not thought that further description 35 thereof is necessary for a complete understanding.

By reason of the releasable engagement of the detent shoulders 67 with the levers 64, after an arm 61 has operated to slide 40 one of the fingers 19 to its rearward position, the stopping of the finger at its rearward position, will cause the latter to offer a resistance or obstruction to the arm 61 and sufficiently to overcome the locking effect 45 of the detent shoulder 67 of the corresponding lever 64 and thereby release said lever so as to permit of the return of said arm to initial position by the corresponding spring 62.

50 In order to apprise of the fact that a conveyer car is empty, at each floor at the down-going side of the conveyer, below the upper floor and excepting the lower floor, an electric light 68 will be provided above 55 the loading opening 59. An indicating light is not provided at the upper floor because all cars passing this floor will necessarily be empty, and a light is not provided at the lower floor, because loading is never 60 done from this floor. Also, excepting each floor above the lower floor at the up-going side of the conveyer and excepting the top floor, an indicating light 68 will also be arranged. Such a light is not arranged at 65 the lower floor because all cars will be

empty as the same pass this floor, and a light is not arranged at the top floor because a car is never loaded from this floor.

Each of the lights 68 is interposed in a branch wire 69 which connects with one of the line wires 70 of a source of electrical energy 71. The branch wires 69 are connected with trolley wires or elongated contacts 72 which are provided immediately above each floor at the down-going side of the conveyer, which is provided with one of the lights 68 and immediately below each floor at the up-going side of the conveyer, which is provided with a light 68. The other side of the source of electrical energy 71 is connected with a trolley wire 73 which extends parallel with the wires 72, said wires 72 and 73 being mounted upon the channel guides 7 at one side of the shaft 1, as clearly shown in Fig. 5. Provided upon each of the conveyer cars are two trolley wheels 74 and 75 which are mounted upon but insulated from a supporting arm 76 which projects from the car, as shown in said figure. The trolley wheels 74 and 75 are adapted for contact with the trolley wires 72 and 73 respectively. The channels 7 adjacent the trolley wheels 74 and 75 are formed with flanges 76' which serve as guides to hold said trolley wheels in engagement with the trolley wires, as clearly shown in Fig. 5. Said trolley wheels 74 and 75 are connected by means of wires 77 and 78 respectively with contacts 79 and 80 arranged upon the car, as clearly shown in Figs. 4, 7 and 8. The contact member 79 of each car is mounted upon and insulated from the plate 14 of the car, the contact 80 being mounted upon and insulated from one of the levers 81 which are fulcrumed intermediate their ends as at 82 to the bars 20 at one side of each car.

The arrangement is such, as will be seen that, when the rearward end of the lever 81 carrying the contact 80 is rocked downwardly, said contact will engage with the corresponding contact 79 in order to close the circuit between the corresponding trolley wheels 74 and 75, and so that when said trolley wheels engage simultaneously with the trolley wires 72 and 73 coöperating therewith, the circuit through the source 71 will be closed in order to light the lamp 68 which corresponds with the trolley wire 72 with which the trolley wheel 74 is engaging. Coöperating with each of the levers 81 is a leaf spring 83 which serves to normally hold the outer end thereof in outward position, this being the normal position of said levers except when the car is loaded. 115 When the car is loaded, the weight of a package or of the load upon said levers will rock the outer ends thereof inwardly or downwardly against the tension of the springs 83 which coöperate therewith. At 120 125 130

the reverse side of each car are also provided levers 81' corresponding with the levers 81 which are fulcrumed at 82'. Corresponding levers 81 and 81' are operatively connected by links 84 which engage with a rocker arm 85 which is pivoted medially of its ends as at 86, as clearly shown in Fig. 7. With this arrangement, it will be seen that, the placing of a package upon either side of the car, that is during down-going movement or up-going movement of the car will have the same effect. The rearward ends of all of the levers 81 are secured together by a connecting bar 87, so that the operation of any one of said levers will have the effect of moving all of said levers. A number of levers are provided, as shown, in order to insure engagement with a package of any size which may be positioned at any location upon the car.

With the construction set forth then, it will be seen that, as an empty car approaches any one of the loading openings or loading stations, the signal light 68 arranged above the loading opening, will be lighted to indicate the fact. The rearward ends of the levers 81 are provided with depending arms 88 which engage in openings 89 formed in the plate 14, the lower ends of said arms, upon downward rocking of the rearward ends of said levers and with the fingers 19 positioned at their forward terminals of movement, being adapted to enter slots 90 formed in said fingers in order to lock the latter against rearward movement. With this arrangement, it will be seen that the fingers 19 will be locked against rearward movement until a package is placed upon the car. Upon the placing of a package upon the car, the levers 81 and 81' will be depressed so as to move the members 88 to releasing position in order to permit of the desired rearward movement of any one thereof. Through the yielding locking of the levers 64 in lowered position, in the event of one of the levers 64 being operated to set one of the arms 61 without a package having been placed upon the succeeding car, the adjusted arm 81 in engaging with the corresponding finger 19 would not move the latter rearwardly, but would itself be rocked rearwardly by said finger to initial position, the pressure upon said arm 61 being sufficient to overcome the frictional locking of the corresponding lever 64 in lowered position.

With this arrangement then, it will be seen that the fingers 19 will be locked against rearward movement except when a package is arranged upon the car. When this is done, the consequential downward rocking of the forward ends of levers 81 will have the effect of raising the members 88 out of engagement with the slots 90 so as to unlock the fingers 19 and permit of rearward move-

ment thereof. At the bases of back-forming members 18' are provided forwardly projecting plates 91 which serve to prevent contact of the packages or articles placed upon the cars with the rearward ends of levers 81 or the portions thereof beyond the pivots 82 and 82' of said levers.

In the operation of the conveyer, the chains 6 will be constantly driven at a comparatively low rate of speed, or at such a speed as to permit of loading of the cars as the same pass the loading openings 59 and 60. After the loading of the car or before, if desired, the lever 64 is actuated to adjust the setting arms 61 for effecting unloading of the car at the floor desired. The proper lever 64 having been adjusted, as the succeeding car passes the arms 61, one of the fingers 19 will be moved rearwardly. As the car approaches the objective unloading opening, the rearwardly projecting finger 19 will engage with the lug 51 or 51', as the case may be, corresponding with that opening, and move the same in order to rock the unloader 40 or 40' coöperating therewith upwardly into engagement with the package which will discharge the same through the corresponding unloading opening 38 or 39. The back-forming members 18' of each car are curved forwardly, as shown, in order to hold the package upon the unloading fingers in the upward rocking thereof. Also, the outer ends of the fingers of the unloading device 40 coöperating with the up-going side of the conveyer will be turned upwardly, as at 92 as shown, in Fig. 1, in order to insure the engagement of said fingers with the package engaged.

The signal light 68 will serve, as above mentioned, to apprise an operator stationed at any one of the loading floors or stations of the approach of an empty car so that as the latter passes the loading opening, the package may be placed upon the car.

With a construction as set forth then, it will be seen that a conveying apparatus is provided wherein, after loading of a car and adjustment of certain levers, the unloading of the car at any floor or station desired will be automatically effected.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In a conveying apparatus; a carrier; means for propelling said carrier; a series

of loading stations and a series of unloading stations which are passed by said carriers when in motion; unloading mechanism at each of said unloading stations; a series of 5 movable devices out of alinement with one another with respect to the lines of travel of the conveyer, one at each unloading station adapted, when actuated to operate the corresponding unloading mechanism; a plurality of 10 movably mounted members carried by said carrier adapted each, upon adjustment thereof to operative position, to engage with one of said devices for actuating the corresponding unloading mechanism; means 15 for adjusting any one of said movable members to operative position; and means adapted, upon adjustment of one of said movable members to operative position, to lock the other of said members in inoperative 20 position, substantially as described.

2. In a conveying apparatus; a carrier; means for propelling said carrier; a series of loading stations and a series of unloading stations which are passed by said carriers when in motion; unloading mechanism at each of said unloading stations; a series 25 of movable devices out of alinement with one another with respect to the lines of travel of the conveyer, one at each unloading station adapted, when actuated to operate the corresponding unloading mechanism; a plurality of movably mounted members carried by said carrier adapted each, upon adjustment thereof to operative position, to engage with one of said devices for actuating the corresponding unloading mechanism; means for adjusting any one of said movable members to operative position; and means controlled by the operative movement of any 30 one of said movable members adapted, upon adjustment of one of said movable members to operative position, to lock the other of said members in inoperative position, substantially as described.

45 3. In a conveying apparatus; a carrier; means for propelling said carrier; a series of loading stations and a series of unloading stations which are passed by said carriers when in motion; unloading mechanism at each of said unloading stations; a series 50 of movable devices out of alinement with one another with respect to the lines of travel of the conveyer, one at each unloading station adapted, when actuated to operate the corresponding unloading mechanism; a plurality of 55 movably mounted members carried by said carrier adapted each, upon adjustment thereof to operative position, to engage with one of said devices for actuating the corresponding unloading mechanism; means for adjusting any one of said movable members to operative position; and pivoted 60 levers carrying detents coöperating with said movable members adapted, upon adjustment of one of said movable members to opera-

tive position, to lock the other of said members in inoperative position, substantially as described.

4. In a conveying apparatus, a carrier; means for propelling said carrier; a series of loading stations and a series of unloading stations which are passed by said carriers when in motion; unloading mechanism at each of said unloading stations; a series 75 of movable devices out of alinement with one another with respect to the lines of travel of the conveyer, one at each unloading station adapted, when actuated to operate the corresponding unloading mechanism; a plurality of movably mounted members carried by said carrier adapted each, upon adjustment thereof to operative position, to engage with one of said devices for actuating the corresponding unloading mechanism; means for adjusting any one of said movable members to operative position; and detents 80 adapted for engagement with recesses provided in said movable members whereby, upon adjustment of one of said movable members to operative position, the other of said members will be locked in inoperative position, substantially as described.

5. In a conveying apparatus, a carrier; means for propelling said carrier; a series of loading stations and a series of unloading stations which are passed by said carriers when in motion; unloading mechanism at each of said unloading stations; a series of 95 movable devices out of alinement with one another with respect to the lines of travel of the conveyer, one at each unloading station adapted, when actuated to operate the corresponding unloading mechanism; a plurality of movably mounted members carried by said carrier adapted each, upon adjustment thereof to operative position, to engage with one of said devices for actuating the corresponding unloading mechanism; means for adjusting any one of said movable members to operative position; and a plurality 100 of yieldingly mounted detents connected together for unisonous movement, said detents being adapted for coöperation with said movable members and adapted, upon adjustment of one of said movable members to operative position, to lock the other of said members in inoperative position, substantially as described.

6. In a conveying apparatus, a carrier; means for propelling said carrier; a series of loading stations and a series of unloading stations which are passed by said carriers when in motion; unloading mechanism at each of said unloading stations; a series of 110 movable devices out of alinement with one another with respect to the lines of travel of the conveyer, one at each unloading station adapted, when actuated, to operate the corresponding unloading mechanism; a plurality of shiftably mounted 115

- members carried by said carriers adapted each, upon shifting thereof to operative position, to engage with one of said devices for actuating the corresponding unloading mechanism; means for shifting any one of said shiftable members to operative position; and a plurality of pivoted levers carrying detents coöoperating with said shiftable members whereby, when one of said 5 members is shifted to operative position, the other of said members will be automatically locked in inoperative position, substantially as described.
7. In a conveying apparatus, a carrier; 15 means for propelling said carrier; a series of loading stations and a series of unloading stations which are passed by said carriers when in motion; unloading mechanism at each of said unloading stations; 20 a series of movable devices out of alinement with one another with respect to the lines of travel of the conveyer, one at each unloading station adapted, when actuated to operate the corresponding unloading mechanism; a plurality of movably 25 mounted members carried by said carrier adapted each, upon adjustment thereof to operative position, to engage with one of said devices for actuating the corresponding unloading mechanism; means for adjusting any one of said movable members to operative position; and depressible means on the carrier for locking said movable members in inoperative position except 30 when an article is placed upon the carrier, substantially as described.
8. In a conveying apparatus, a carrier; 35 means for propelling said carrier; a series of loading stations and a series of unloading stations which are passed by said carriers when in motion; unloading mechanism at each of said unloading stations; a series of movable devices out of alinement with one another with respect to the 40 lines of travel of the conveyer, one at 45
- each unloading station adapted, when actuated to operate the corresponding unloading mechanism; a plurality of movably mounted members carried by said carrier adapted each, upon adjustment thereof to 50 operative position, to engage with one of said devices for actuating the corresponding unloading mechanism; means for adjusting any one of said movable members to operative position; and pivotally 55 mounted depressible means on the carrier for locking said movable members in inoperative position except when goods are loaded upon the carrier, substantially as 60 described.
9. In a conveying apparatus, a carrier; 65 means for propelling said carrier; a series of loading stations and a series of unloading stations which are passed by said carrier when in motion; unloading mechanism 70 at each of said unloading stations; a series of movable devices out of alinement with one another with respect to the lines of travel of the conveyer, one at each unloading station adapted, when actuated, to operate the corresponding unloading mechanism; a plurality of shiftably mounted 75 members carried by said carrier adapted each, upon shifting thereof to operative position, to engage with one of said devices for actuating the corresponding unloading mechanism; means for shifting any one of said shiftable members to operative position; and means on the carrier for locking 80 said shiftable members in inoperative position except when an article is placed upon the carrier, substantially as described.
- In testimony whereof I have signed my name to this specification in the presence of two subscribing witnesses.
- RAYMOND J. FAHLE.
- Witnesses:
- JOSHUA R. H. POTTS,
HELEN F. LILLIS.
